tion of Delaware

Application September 16, 1932, Serial No. 633,413

5 Claims. (Cl. 62—117)

This invention relates to an improved method and apparatus for cooling air and controlling the humidity thereof in enclosures for people, particularly in railroad cars where it is necessary 5 to contend with highly variable factors.

In air conditioning and cooling of railroad cars, several well-known difficulties are encountered, the principal one of which is effecting the necessary cooling action when the train is stopped or 10 running below a predetermined speed, it being understood that while the train is travelling under normal speeds sufficient power may be obtained either mechanically directly from an axle or from an axle driven generator for operating 15 the equipment. Due to the failure of this source of power when the train stops or slows down below a predetermined speed, various means have heretofore been attempted for maintaining the cooling apparatus in operation. For instance, in 20 one type of cooling apparatus where a mechanical refrigeration compressor is employed, the compressor is operated by an auxiliary source of power such as a gasoline engine automatically started when the train stops. In other cases, 25 storage batteries have been employed to operate the compressor. In arrangements of these kinds the auxiliary power sources must be relatively large for driving the compressor because of the necessity of immediately producing the entire refrigeration required at any particular moment. 30 These requirements are appreciably greater when the train is standing still over when it is moving due to the car doors being usually open with passengers entering and leaving the cars with consequent large amount of external heat and humidity being admitted.

Therefore it is desirable to have cooling equipment which can provide the relatively large refrigeration requirements when a train is standing still and yet not subject the mechanical refrigeration apparatus to large loads during such periods. In this respect, in another type of car cooling equipment an attempt has been made to build up a reserve capacity of refrigeration by 45 frosting and defrosting the evaporator coils. Inasmuch as this system requires taking air from the car and circulating it over the evaporator it is seen that the reserve capacity is dependent upon the existence of an adverse condition which 50 it is desired to eliminate, namely, an excess amount of humidity. If this is removed from the air to build the reserve, it will nevertheless be returned to the air at a later period when used as a reserve thus defeating at least partially, one 55 useful purpose of air conditioning, namely, uni-

form low humidity. Moreover this stored-up humidity, as such a reserve might be called, is returned to the car usually at the most unfavorable time as when passengers are opening the car doors which allows admission of unconditioned exterior atmosphere with all of its humidity, this accumulated natural and unnatural humidity adding unnecessary discomfort for the passengers. This system also has the disadvantage that if there is very little or no excess humidity such as when travelling across arid lands, then the system will fail in its principal purpose of providing a reserve. Hence it is seen that the available quantity of reserve medium is a highly variable factor which added to the inherent va- 15 riable conditions in car cooling renders such a system objectionable.

In my improved invention it is one object to provide a car cooling system having an improved method and apparatus for building a reserve ca- 20 pacity during normal running of the train for use while the train is standing still and particularly for more definitely permitting the temperature and humidity to be maintained under normal control and without having the reserve 25 capacity directly depend upon or be in a position to aggravate an adverse condition which it is desired to control. More specifically these ob- 30 jects are accomplished by circulating a liquid cooling medium such as water over evaporator coils of a refrigeration system and freezing a part of such water on to the surface of said coils while the remaining unfrozen portion of the cool- 35 ing medium is uniformly and continuously circu- 40 lated from the tank, in which the evaporator coils are disposed, through a suitable air cooling ra- 45 diator and back to the evaporator where it flows over the coils and ice thereon. In this way it is possible to accomplish the improved result of not only cooling the car by the regular refrigeration apparatus and water circulating system during travelling of the train but also of building a 50 reserve supply of refrigeration such as ice and controlling more uniformly the temperature and humidity of the car. At the same time it is also possible to design a system for a definite reserve capacity independently of humidity conditions either within the car or the exterior atmosphere and by formation of ice a large reserve capacity can be built up in a relatively small space due to 55 the large latent heat factor in transforming water into ice or vice versa. Also the freezing of only a part of the liquid in the evaporator tank avoids choking of the system such as would occur in the event that the entire amount of liquid 55

in the evaporator tank was frozen. To insure that choking will not occur, the quantity of circulated cooling medium is limited to less than the total volumetric capacity of the system thus permitting the evaporator tank to be only partially filled with liquid and preferably to have the normal level of the liquid below the evaporator coils or at least to have the evaporator coils only very slightly submerged.

To obtain the best results in a system of this kind it is preferable to spray the returned cooling liquid over the evaporator coils, thus creating not only better transfer of heat from the returned liquid but also permitting more efficient formation of ice over the evaporator coils. The ice formation may be in the nature of icicles which creates not only a large surface of reserve refrigeration whereby sprayed water may be quickly cooled when the train is standing still but also the icicles will be of irregular formation around the evaporator coils or pipes thus causing certain portions of the pipes to have only a thin film of ice thereon or possibly no ice at all which bare portions of the pipe would permit a higher degree of heat transfer from the flowing water during normal travelling of the train. It will of course be understood that in the event a portion of the evaporator coils is submerged, ice may then form solidly and uniformly around such pipes but in that event the upper unsubmerged pipes will function to permit more efficient heat transfer during normal running of the train.

Other and more specific objects and advantages will be more apparent from the following description of the accompanying drawings in which:

Fig. 1 is a side elevation of a railroad car diagrammatically shown as equipped with my improved cooling system;

Fig. 2 is a plan view of Fig. 1;

Fig. 3 is a combined schematic and mechanical diagram of my improved system; and

Fig. 4 is a fragmentary longitudinal section of evaporator pipes with a fin construction.

In the illustrated embodiment of the invention I have shown a standard passenger railroad car 1 having a suitable electrical generator 2 driven through suitable belt gearing from an axle of car wheel 3. Various types of gearing may be employed but the specific construction of such does not constitute a part of my invention. The generator supplies direct current, during running of the train, through wires 4 to a rotary converter 4' which in turn supplies alternating current through wires 5 to an electric motor 6 which drives a refrigeration compressor 7 preferably by a belt although various other types of gearing may be employed. The compressor may be of any usual type although preferably of the piston and cylinder type. The use of a rotary converter permits an alternating current compressor motor to be used thus facilitating plugging into regular supply sources at railroad stations in case it is desired to operate the compressor for an extended period of time without relying upon the reserve capacity.

Any suitable refrigerant is compressed and discharged under high pressure through pipe 8 to a condenser 9 preferably of the air cooled type enclosed within a casing 10 having an inlet 11 and outlet or outlets 12 the condenser air being circulated by suitable fans 13 driven from a common electric motor 14. The condenser may be of any usual form but is diagrammatically shown as comprising two headers connected with a series of pipes provided with fins. A discharge pipe 15

leads from the one header to a float controlled expansion valve 16, this system being preferably of the flooded type. The refrigerant flows through a series of evaporator coils 17 and out to the low pressure pipe 18 to the compressor 7 thus completing the refrigerating circuit. The evaporator may comprise a series of plain pipes or the pipes may be provided with a series of either annular or spiral fins or other forms of heat radiating surfaces 17' whichever may be desired. It will be understood from the following description that these fins not only perform the function of increasing the heat transfer surface but also of providing improved means for assisting in building up ice for reserve refrigeration capacity. The equipment so far described is supported in any suitable manner beneath the car.

To effect the necessary air conditioning there is provided within the car, preferably near the vestibule roof, a radiator 18 of any suitable form to which chilled water is circulated from the evaporator tank 19 through pipe 20, pump 21 and pipe 22 through radiator 18' and back through pipe 23 to a pipe or series of spray pipes 24 disposed over the top of the evaporator coils 25 and provided with suitable spray openings or nozzles diagrammatically indicated at 25 whereby the returned cooling liquid medium will be sprayed over the surface of the evaporator coils to trickle thereover and accumulate in the bottom of evaporator casing 19, the accumulated water being maintained at a liquid level 26 which preferably is below or only submerges the evaporator pipes to a limited extent.

To cool the air within the car there is provided an air distributing duct or ducts 27 extending lengthwise of the car and preferably adjacent the roof on the inside thereof or on the outside of the half deck, these air ducts being provided with suitable lateral outlets into the car. The radiator 18' is enclosed within a suitable casing 28 which has closed communication with ducts 27. The air to be conditioned is circulated over radiator 18' by a fan or fans 29 driven preferably by a common motor 30. Inasmuch as the casing 28 has direct communication with the interior of the car it is seen that the return air from the car may pass through a suitable adjustable vaned opening 31 and filter 32 and thence through the radiator 18'. If desired under certain circumstances a portion of the air may be recirculated, without passing through the radiator, as by the provision of an adjustable vaned inlet 33 which will allow air to pass directly to the fans. To provide a fresh supply of air an adjustable vaned opening 34 may be placed in communication with the exterior air through a suitable passage 35 provided preferably with a filter 36. The various adjustable vanes may be automatically controlled by usual thermostats or humidistats.

It is preferable that simple means be provided for controlling the volume of circulated cooling liquid and to accomplish this there is provided a pipe 40 for bypassing returned fluid from pipe 23 to pump 21 thereby cutting out fluid to the sprays 25. This bypass may be suitably controlled by a thermostat or humidistat diagrammatically indicated at 41.

In order that this system may be as self-contained and free from difficulty as possible there is provided in one aspect of the invention an improved automatic water make-up for the circulated cooling water comprising a pipe 37 allowing communication between a drip space below 70

5 radiator 18' and the evaporator casing 18 whereby condensate on radiator 18', representing humidity removed from within the car, will flow to the evaporator tank and be added to the circulated cooling liquid thus insuring not only that proper care will be taken of any collected moisture but also of avoiding the necessity of making up evaporated liquid from the cooling system and in addition insuring that the humidity and 10 temperature of the air within the car may be properly controlled.

10 As a result of my improved combination, I am able during travelling of the train to cause a certain amount of ice 43 to be formed over the surface of the evaporator coils without completely freezing across the passageways through the evaporator thereby allowing the unfrozen water to pass through to the bottom of the evaporator tank from which it is circulated to radiator 18 for cooling the car during normal travelling of the train. When the train stops, pump 21 will be constantly driven by its electric motor 38 supplied with a small amount of electric current from the usual car storage battery thereby to 15 continue cooling of the car even though compressor 1 is stopped. The circulated cooling water will continue to flow over the surface of the evaporator coils and melt the ice thereon which constitutes the reserve capacity, there being no 20 change in temperature of the water from that when the compressor is running because any excess refrigeration at any given time will simply be transformed into reserve capacity. The maximum capacity can be suitably designed for any 25 given set of travelling conditions as by adjusting the compressor capacity. It will be further seen that my improved method and apparatus will form a relatively large ice surface which will insure maximum efficiency in the use of the reserve capacity when the train is stopped, and while the train is running the irregular formation 30 of ice on the evaporator coils will insure acceptable efficiency inasmuch as the less thickly coated portions of the coils will permit the proper degree 35 of heat transfer. While the ice is shown in Fig. 3 as being in the nature of icicles with the lower coils less thinly coated, yet it will be understood that if desired the evaporator coils may be provided with annular or spiral fins 11', preferably 40 relatively closely spaced, thus insuring a very 45 large surface area upon which the reserve capacity of ice may form, the ice in this case being relatively thinly spread over the entire surface thus permitting a more uniform rate of heat 50 transfer over the entire evaporator surface. While it is preferable that water be used other liquids might be employed but it is more efficient 55 to use water on account of ice forming in a limited space and having a high latent heat factor and also because water has high specific 60 heat which increases its storage capacity.

65 From the foregoing description it is seen that I have provided an improved method for conditioning air, especially for railway cars, consisting in operating a refrigeration system or apparatus during travelling of the car preferably by receiving its power from a generator driven by the car axle, circulating a liquid preferably water in heat 70 interchanging contact with the evaporator of the refrigeration system so as to chill the liquid, causing car air to be cooled by said circulating cooled liquid, that is any air that it is desired to have cooled for the interior of the car, and then freezing a portion of the circulated liquid preferably 75 directly on the evaporator pipes or coils

while preferably continuing the circulation of the remaining portion of the liquid which preferably only partially fills an evaporator tank to thus permit unsubmerged ice covered portions of the evaporator, whereby the frozen liquid such as ice 5 is adapted to keep the circulating liquid chilled when the refrigeration apparatus is not in operation as when the car is stopped or running below a predetermined speed. From such a method of operation it is seen that the refrigeration apparatus 10 preferably has a refrigeration capacity in excess of normal travelling requirements, whereby the ice may be formed on the evaporator coils even while normal cooling is being effected. The degree of excess refrigeration may be only slight 15 or large depending upon the character of train service such as frequency of stops and length of continuous running. In certain limited cases it may be desirable, in another aspect of the invention, to build the ice reserve capacity primarily or 20 wholly while the train is in a terminal station as by using the external source of current, but in any of these arrangements it will be seen that the remaining unfrozen portion of the liquid is kept circulating and that the single circulating liquid 25 serves the multiple functions of providing a medium for the solidified reserve, a circulating medium for normal cooling when the train is travelling, and a medium of taking up the reserve capacity. In each case the medium is maintained 30 in a closed system or at least in a system having definite volumetric limits and capacity and that the medium is of fixed volume, aside from make-up, preferably less than that of the closed system. This has the advantage that the reserve ice is to 35 a very large extent, spaced from the evaporator tank walls by an insulating air space. It will of course be understood that during winter months the radiator 18' may be connected to the heating lines of the train and warm air distributed 40 through the car by use of fans 29.

45 In order to operate the reserve refrigeration capacity as when the train is stopped or running below a predetermined speed the circulating pump motor 38 may be supplied with current 45 from a storage battery 45 which is automatically connected to the pump motor or to generator 2 in accordance with the generator voltage as by any suitable voltage controlled switch mechanism used for this purpose and diagrammatically indicated at 46. If desired usual connections may be employed for simultaneously charging the battery and operating the pump motor by current supplied from the generator, but upon slowing down or stopping of the train the battery will 50 supply current only to the pump motor to maintain continued circulation of the chilling liquid. It will also be understood that in the broad aspects of this invention the evaporator coils or pipes may be divided into sections whereby one 55 section would serve primarily for chilled circulating liquid without an ice reserve while the other section could be used primarily or solely for building an ice reserve, this arrangement necessarily involving two expansion valves or flooded systems 60 operating at different pressures which could be employed especially with a multiple effect compressor.

65 It is thus seen that my improved method and apparatus provides a very simple system and 70 equipment for insuring constant temperature conditions of a railroad car without the need of a large auxiliary source of power for operating the refrigeration compressor when the train is standing still or when running below a predeter- 75

mined speed and in addition is self-contained and economical in operation. Hence not only is the initial cost and maintenance of such auxiliary power eliminated but also less weight is added to the car.

5 It will of course be understood that various changes may be made in the construction and arrangement of parts and details of design without departing from the spirit of the invention as set forth in the appended claims.

10 I claim:

15 1. The method of conditioning air for railway cars consisting in operating a refrigeration system during travelling of the car, circulating liquid in heat interchanging contact with said system so as to chill the liquid, causing car air to be cooled by said circulating chilled liquid only during travelling of said car, freezing only a portion of said liquid, and circulating the remaining unfrozen portion thereof whereby the frozen liquid is adapted to keep the circulating liquid chilled as when the car is stopped or running below a predetermined speed, the quantity of circulated cooling medium being less than the total 20 volumetric capacity of the system.

25 2. An air conditioning system for railway cars comprising, in combination, a refrigeration apparatus including an evaporator, a liquid tank in which said evaporator is disposed, a radiator for cooling the car air, and means for circulating liquid from said tank to said radiator for cooling the same, said refrigeration system having refrigeration capacity, in excess of that normally required during travelling of the car but adapted 30 to cause only a portion of said circulating liquid to be congealed by said evaporator whereby when the car is stopped said radiator will be maintained cooled by continued circulation of the remaining uncongealed portion of said liquid over the congealed liquid in said evaporator, the quantity of circulated cooling medium being less than the total volumetric capacity of the system.

35 3. An air conditioning system for railway cars comprising, in combination, a refrigeration apparatus including an evaporator, a tank in which said evaporator is disposed, a liquid partially filling said tank so that at least a portion of said evaporator is unsubmerged, a radiator for cooling the car air, and means for circulating said liquid from said tank to said radiator and then back to said tank to flow over said evaporator after which the liquid accumulates in the bottom of said tank for continuous recirculation, said refrigeration system having refrigeration capacity, in excess of that normally required dur-

40 ing travelling of the car, for causing only a portion of said circulating liquid to be frozen by said evaporator whereby when the car is stopped said radiator will be maintained cooled by continued circulation of the remaining unfrozen portion of said liquid over the frozen liquid in said evaporator.

45 4. An air conditioning system for railway cars comprising, in combination, a refrigeration apparatus including an evaporator, a tank in which said evaporator is disposed, a liquid partially filling said tank so that at least a portion of said evaporator is unsubmerged, a radiator for cooling the car air, and means for circulating said liquid from said tank to said radiator from which the liquid is returned to said tank, said circulating system including means for spraying the returned liquid over said evaporator after which the liquid accumulates in the bottom of said tank for continuous recirculation, and said refrigeration system having refrigeration capacity, in excess of that normally required during travelling of the car, for causing only a portion of said circulated liquid to be frozen by said evaporator whereby when the car is stopped said radiator will be maintained cooled by continued circulation of the remaining unfrozen portion of said liquid over the frozen liquid in said evaporator.

50 5. An air conditioning system for railway cars comprising, in combination, a refrigeration apparatus including an evaporator, a liquid tank in which said evaporator is disposed, a radiator, means for causing air to flow over said radiator and into the interior of the car, a liquid system connecting said evaporator tank with said radiator, pumping means for effecting said liquid circulation, said refrigeration apparatus having capacity to congeal only a portion of said circulating liquid while the remaining uncongealed portion continues to be circulated, means for operating said pump when said refrigeration apparatus is not in operation thereby maintaining continued circulation of the liquid and consequent cooling of the radiator by said congealed liquid, said refrigerating apparatus having a capacity in excess of that normally required during travelling of the car thereby to congeal only a portion of said circulating liquid for use when said car is standing still, and means for bypassing circulated liquid around said evaporator automatically in accordance with predetermined car air conditions, the quantity of circulated cooling medium being less than the total volumetric capacity of the system.

CHARLES R. NEESON. 55

CERTIFICATE OF CORRECTION.

Patent No. 2,027,058.

January 7, 1936.

CHARLES R. NEESON.

It is hereby certified that error appears in the printed specification of the above numbered patent requiring correction as follows: Page 4, First column, line 17-18, claim 1, strike out the words "only during travelling of said car" and insert the same after "liquid" and before the comma in line 19; and that the said Letters Patent should be read with this correction therein that the same may conform to the record of the case in the Patent Office.

Signed and sealed this 25th day of February, A. D. 1936.

Leslie Frazer
